mesne assignments, to Loewe Radio, Inc., a cor-
poration of New York

Application June 3, 1933, Serial No. 674,206
In Germany June 7, 1932

10 Claims. (Cl. 178—7.5)

It is known for the purpose of simplifying the receiving arrangement to transmit by the sender at the end of each line a short synchronising impulse, and at the end of each image a long synchronising impulse, the amplitude of which is greater than the maximum amplitude of the image potential.

It has been proposed to separate this synchronising impulse at the receiving end from the image potential with the assistance of a compensating potential supplied by a counter-battery, which compensating potential acts in opposition to the voltage mixture picked up and amplified by the receiving apparatus, and which has at least to be equal to the maximum image potential and smaller than the synchronising potential. The use of a compensating potential of this nature for separating the synchronising impulse from the image potential is difficult if the fluctuations in intensity of the strength of field at the receiver are considerable.

Further difficulties arise owing to the fact that the absolute value of the potentials received varies very greatly at the receiver upon manipulation when means are provided for regulating the contrast in the picture. The variable nature of the potentials renders it necessary to make the compensating potential correspondingly variable. The methods hitherto proposed employ for this purpose the derivation of a mean value from the rectified synchronising impulses i. e. in such a manner that to the grid of a special valve a negative potential is given, which is proportional to the average intensity of the reception, and allows only the amplitude peaks, i. e. the synchronising impulses to pass to the synchronising means.

Since, however, the synchronising impulses cannot be transmitted, or at least only with very great difficulties, true to form, the derivation of a mean value is not sufficient in all cases to ensure correct synchronisation.

According to the invention the synchronising impulses which are of a sign or polarity opposite to the image contents frequencies are obtained from the received voltages by the use of a variable regulating device, which is controlled by all the received voltages, and generates a counter-potential, which allows the passage merely of amplitude peaks, i. e., the synchronising potentials. The said device consists of a separating filter comprising a thermionic valve and a resistance in parallel therewith, in connection with a condenser.

For carrying out the method according to the invention preferably an apparatus for controlling

the movement of the light ray is employed, for the control of which very low control potentials (up to approximately .5 volt) are sufficient. An arrangement of this kind is described, for example, in application for Letters Patent of the United States, Ser. No. 668,940, filed May 3, 1933.

The invention will be more fully understood by reference to the appended drawing, which in Fig. 1 shows by way of example an arrangement for carrying out the method according to the invention, while Fig. 2 is a detail view illustrating a modification and Fig. 3 is a diagram hereinafter referred to in explaining the operation of my improved television apparatus. In Fig. 1, 1 is the receiving and amplifying arrangement with 15 apparatus 2 for regulating the contrast on the received picture. By the said receiver and amplifier, the potential mixture is conducted on the one hand over the line 3 direct to the light control apparatus or image reproducing device, preferably a Braun tube, and on the other hand is passed on via the condenser 5 (of, for example, 10^{-4} μ f.), to the controlling means. 6 is a diode with the hot cathode 25 and the anode 24. Instead of the diode any suitable type of electron 25 device, for instance a multi-electrode valve, may be employed. 16 and 17 are two grid-controlled glow-discharge tubes, preferably of that type in which the starting of the current is determined by the grid potential, but in which the current 30 may be interrupted only by reducing the plate voltage below its critical value. The tubes 16 and 17 are provided with the grids 27 and 30, the cathodes 28 and 31 and the anodes 26 and 29. The anodes 26 and 29 are linked up with the 35 grounded positive pole of the anode battery 8. The cathodes are connected with the condensers 14 and 15, which are charged with the assistance of the charging tubes 18 and 19. During the charging the potential of the cathodes is shifted 40 into negative. The grid of the image control tube 17 is connected through the medium of the resistance 12 and the condenser 13, which are selected in such fashion (for example at .1 megohm and 1 microfarad) that the high frequency parts of 45 the potential mixture including the line synchronising impulses are withheld from the grid, and through the medium of the resistance 9, which may be selected at approximately 5×10^6 ohms, with a tapping point of the battery 8, which tapping point, of course, is negative in relation to the positive pole of said battery. To the same tapping point there is connected over the line 7 and the resistance 9, through the resistance 10 and the condenser 11, which act as a filter for the 55

high frequency parts of the potential mixture and may be selected at approximately .1 megohm and $10^{-2} \mu\text{f}$, the grid 27 of the glow tube 16 of the line-control apparatus. The line-control potential is taken from the terminal 20, the image-control potential from the terminal 21. The value of the resistances 10 and 12 and the condensers 11 and 13 may, generally speaking, preferably be such that the time constants τ^1 of the circuit 10, 11 and τ^2 of the circuit 12, 13 are approximately $\tau^1=10^{-3}$ and $\tau^2=10^{-1}$.

In Fig. 1, I have shown heating filaments immediately below the cathodes of the tubes or valves 6, 16, 17, 18, and 19, and I have also indicated a heating battery, that is, a battery for supplying the heating current to the filament located below the cathode 25 of the tube or valve 6. It will be understood that the heating filaments of the other tubes or valves are similarly connected with a source of current.

The operation of the apparatus is as follows: Whilst the anodes 26, 29 are at a constant positive potential the grids 27, 30 of the glow tubes 16, 17 receive a strong negative bias in relation to the respective cathodes. The extent of the bias is determined by the tapping at the battery 8. Upon the charging of the condensers 14 and 15 by the charging tubes 18 and 19 the potential of the cathode 28 or 31 respectively is shifted into negative until the hot cathode has become negative to such extent that the blocking effect of the grid ceases and the discharge occurs. As described in detail below, the synchronising potential is conducted to the grid. By suitable selection of the grid bias it is possible to adjust the deflecting potential apparatus in such fashion that the same is capable of producing either both free as well as enforced relaxation oscillations, or merely enforced, i. e. synchronised relaxation oscillations. The latter case occurs when the negative grid bias is selected to be so high that the cathode is unable to reach the potential necessary for discharge. In this case discharge is only possible when the potential of the grid has been shifted to the requisite extent into positive by means of additional potential (synchronising potential). According to the invention, the grid bias is preferably so adjusted that a very small variation in potential of the grid (approximately .1 to .5 volt) is quite sufficient to produce a discharge. This additional synchronising potential is taken from the amplitude mixture with the assistance of the regulator 6. The diode 6 acting as a variable regulator produces a counter-acting direct potential, by which the negative parts of the amplitude mixture are allowed to pass and the positive parts with the exception of the amplitude peaks of the synchronising impulses are cut off. A complete elimination of the peak potentials cannot take place, as the condenser charge flows off slowly over the large leak resistance 9, so that the counter-potential produced by the variable regulator is at no time able to reach completely the value of the peak potential. The potential of the grid 30 upon the arrival of a long synchronising impulse, and the potential of the grid 27 upon the arrival of every (i. e., both a long as well as a short) impulse, will be shifted to a relatively small extent into positive. This slight displacement of the grid potential is sufficient, when using grid-controlled glow tubes, to control the tube and to synchronise the relaxation oscillations. The synchronisation is accordingly controlled by the peak potential independently of the absolute value of the same. Accord-

ingly, the synchronisation is wholly independent of the absolute value of the image or synchronising potential.

The leak resistance 9 must be sufficiently large to prevent the condenser charge from flowing off too rapidly. The condenser 5 on the other hand requires to be selected in such fashion that the variation in the absolute value of the potentials (contrast regulation or variation in the strength of field) is able to take place with sufficient rapidity.

The deflecting frequency may be varied in the manner known per se by variation of the condenser and of the charging current. This is easily accomplished when the valves 18 and 19 employed for the purpose of charging the condensers 14 and 15 respectively are screen grid valves as indicated in the drawing; I might, however, dispense with the screen grids and their connections, in which case the valves 18 and 19 would be diode valves of the same character as the valve 6.

As set forth in detail in the above, it is possible to adjust the grid bias in such fashion that the deflecting apparatus does not produce any free relaxation oscillations at all, and scanning is initiated only by the synchronising impulses. In many cases, however, it may also be desirable to select the potentials in such fashion that the apparatus is able to generate free relaxation oscillations, and that by reason of the synchronising impulses solely synchronisation of the apparatus takes place.

In further explanation of the principles of my invention, I will now refer to the diagram Fig. 3. It will have been understood from the foregoing description that the impulses reaching the receiver and amplifier 1 from the transmitter are a mixture of frequencies containing the frequency band of the image potentials and also the synchronizing voltages. In Fig. 3, the curve A represents a control potential of maximum amplitude, while curve B corresponds to about the minimum potential required for synchronizing purposes. For initiating the operation of the glow-discharge tubes 16, 17 on the Braun tube or other image-reproducing device, the amplitude peaks of the curve must extend to a certain amount beyond (above) the initiating line indicated at I in Fig. 3.

Under especially favorable reception conditions, the carrier wave may produce potentials such as represented by curve A, which lies entirely above the initiating line and therefore would completely compensate the blocking effect produced by the strongly negative bias potential normally applied to the grid 27, 30 of the glow-discharge tubes 16 and 17 respectively. This undesirable condition is remedied by my invention, according to which adjustments are made which will shift the position of the potential curve A into the negative region, that is to say, below the zero line indicated in Fig. 3. The means employed by me for this purpose, in the embodiments illustrated, consists of the regulating device comprising the condenser 5 and the valve 6 or 6', in conjunction with the resistance 9. This device operates as follows:

When highly positive impulses are received, as indicated by the maximum curve A, electrons are emitted from the cathode 25 of the regulating valve 6 or 6', which cathode is capable of emitting electrons abundantly. The result of such electron emission is to cause the anode 24 to receive a negative charge of increasing strength. This negative charge serves for varying the bias on the

grid 27, 30 of the glow-discharge tubes 16 and 17 respectively. The resistance 9 is of such electrical dimension as to leak off or carry off a portion of the electron charge, to such an extent that the incoming voltage-amplitudes, originally corresponding to the curve A, will correspond to the curve B, located below the zero line and just reaching it at the amplitude peaks, although it is not essential that such peaks should reach the zero line, as long as they exceed the initiating line I. The necessary bias is thus obtained at the grids 27, 30. In this manner I have provided a self-regulating device which controls the amplitude of the synchronizing frequency to such an extent that at every moment the initiating impulse will be determined exactly as to time and amplitude.

It has been ascertained that when employing glow tubes of the grid type it is necessary to screen off completely the entire deflecting device. It has been found desirable to again screen off separately within the screening container all leads conducting fluctuating potentials.

As regards the method according to the invention, it is particularly convenient to employ glow lamps of the grid type in accordance with the above application No. 668,940, having indirectly heated, metallic-vapour, high-emission cathode, argon or nitrogen filling of approximately .1 to 10 mm. pressure, extremely low reciprocal of the amplification factor, and tungsten electrodes. Naturally, the method according to the invention may also be performed with other suitable discharge tubes.

The arrangement according to the invention may be employed in connection with all known control frequency methods. Since when making use of glow lamps of the grid type currents may be produced of almost any desired value, the arrangement may naturally also be employed for the operation of mechanical systems, for example those systems which operate with synchronising motors or the like.

As I have stated above, a multi-electrode valve might be employed instead of the diode 6. Such an arrangement is indicated in Fig. 2, showing a valve 6' which in addition to the anode 24 and the hot cathode 25 includes a grid 6''. In this case the condenser 5 is connected with the grid 6'', the other connections being the same as in Fig. 1.

I claim:

1. In a television reception apparatus comprising a receiving amplifier having an output terminal adapted for connection with an image reproducing device, a gaseous discharge relaxation oscillation generator having means adapted for connection with said image reproducing device, a voltage source and means to connect said high voltage source with said generator, a condenser, a hot-cathode valve, the one electrode of said condenser being connected to the output terminal of said amplifier and the other electrode to an electrode of said valve other than the cathode, a direct current connection from the output of said valve to the input terminal of said generator, a connection between said cathode and another electrode of said valve, a resistance included in the last-mentioned connection, and a connection from said cathode to a negative point of said voltage source.

2. In a television reception apparatus comprising a receiving amplifier having an output terminal adapted for connection with an image reproducing device, a gaseous discharge relaxation os-

cillation generator having means adapted for connection with said image reproducing device, a voltage source and means to connect said voltage source with said generator, a condenser, a hot-cathode valve including a plate and a grid, the one electrode of said condenser being connected to the output terminal of said amplifier and the other electrode to the grid of said valve, a connection from the plate of said valve to the input terminal of said generator, a connection between the plate and the cathode of said valve, a resistance included in the last-mentioned connection, and a direct current connection from said cathode to a negative point of said voltage source.

3. In a television reception apparatus comprising a receiving amplifier having an output terminal adapted for connection with an image reproducing device, a relaxation oscillation generator having means adapted for connection with said image reproducing device, a voltage source and means to connect said voltage source with said generator, a condenser, a hot-cathode two-electrode-valve comprising a plate and a cathode, the one electrode of said condenser being connected to the output terminal of said receiving amplifier and the other electrode to said plate of said valve and to the input terminal of said generator and to said cathode, a resistance included in the connection between said other condenser electrode and said cathode, and a connection from said cathode to a negative point of said voltage source.

4. In a television reception apparatus comprising a receiving amplifier having a terminal adapted for connection with an image reproducing device, an anode voltage source, a relaxation oscillation generator comprising a grid-controlled glow tube, a condenser connected with said tube and means connected with said tube and said condenser, for charging such condenser and producing the relaxation oscillation voltage, means for connecting the cathode of said glow tube with said reproducing device, the plate of said glow tube being connected to said anode voltage source, the one electrode of said condenser being connected to said plate and the other electrode being connected to the cathode of said glow tube and to said relaxation oscillation voltage producing means, a further condenser, a valve having a hot cathode and a plate, a resistance, the one electrode of said last-mentioned condenser being connected to the output terminal of said receiving amplifier and the other electrode to the plate of said valve, a connection from said plate to the grid of said glow tube, another connection from said plate to one point of said resistance, a connection from another point of said resistance to the cathode of said valve, and a connection from said cathode to a negative point of said anode voltage source.

5. An apparatus according to claim 4, in which the capacity of the condenser connected with the valve is of the order of 10^{-4} microfarads, and in which the resistance connected with said valve is of the order of 5×10^6 ohms.

6. An apparatus according to claim 4, in which a screen grid valve is employed as the means for charging the condenser connected with the grid-controlled glow tube.

7. In a television reception apparatus comprising a receiving amplifier having a terminal adapted for connection with an image reproducing device, an anode voltage source, a relaxation oscillation generator, comprising two grid-controlled glow tubes for producing line and image deflect-

ing voltages respectively, a condenser for each of said tubes, a valve associated with each of said tubes and condensers for producing the relaxation oscillation voltages, the plates of said tubes being connected to said anode voltage source, the one electrode of each said condensers being connected to said plates and the other electrode of each being connected to the cathode of the respective tube and to the plate of the 10 respective valves, a further condenser, a hot-cathode valve and a resistance, the one electrode of said further condenser being connected to the output terminal of said receiving amplifier and the other electrode to the input of said hot-cathode 15 valve, a connection from the plate of said valve to the grids of said tubes, another connection from said plate to one point of said resistance, a connection from another point of said resistance to the cathode of said hot-cathode 20 valve, and a connection from said cathode to a negative point of said anode voltage source, and means for connecting the cathodes of said tubes with said reproducing device.

8. An apparatus according to claim 7, in which 25 screen grid tubes are employed as the tubes associated with each of the grid-controlled glow-tubes and their condensers for producing the relaxation oscillation voltages.

9. In a television apparatus comprising a receiving amplifier and a relaxation oscillation 30

generator for producing the cathode-ray deflecting currents, said generator including an electronic tube provided with a grid, a source of electricity connected with said generator and having a tap connected with said grid to supply a biasing voltage, and a regulating device comprising another electronic tube, such last-mentioned tube having an anode and a cathode, said cathode being connected to the above-mentioned tap, and said anode being connected to the grid of the 10 generator tube, the tube of the regulating device being also connected with the output of said amplifier.

10. In a television apparatus comprising a receiving amplifier and a relaxation oscillation generator for producing the cathode-ray deflecting currents, said generator including an electronic tube provided with a grid, a source of electricity connected with said generator and having a biasing tap connected with said grid, and a regulating device comprising another electronic tube, such last mentioned tube having an anode, a cathode, and a third electrode, a condenser the terminals of which are connected with said third electrode and with the output of said amplifier 25 respectively, the cathode of the last-mentioned tube being connected to the above-mentioned tap, and the anode of said tube being connected with the grid of the generator tube.

KURT SCHLESINGER. 30
